MACHINE FOR MAKING PURELY PRESSED
GLASSWAREWalter K. Berthold, Rockville, Conn., assignor to
Hartford-Empire Company, Hartford, Conn., a
corporation of DelawareApplication September 11, 1936, Serial No. 100,246
Renewed December 16, 1939

6 Claims. (Cl. 49—35)

This invention relates to a machine for making either blown or "purely pressed" glassware. By "purely pressed" glassware is meant ware which is produced solely by pressing without the application of any air for the purpose of shaping the ware being produced.

The general object of the invention is to provide means whereby a feeder-fed glassware forming machine for producing glassware by the narrow neck method may also be employed for producing purely pressed ware, thus increasing the utility of such machine. For the purpose of simplicity, the feeder-fed forming machine operating on the narrow neck principle is referred to hereinafter as the "narrow neck" machine or type of machine, and the type of ware produced on said machine is referred to as "narrow neck" ware, irrespective of whether the ware has narrow necks, this term identifying the ware by the method and machine on which it is made.

A more specific object of this invention is to employ a narrow neck machine for making purely pressed ware by utilizing certain of the parts of such machine heretofore used only for actuating the narrow neck forming instrumentalities, for actuating pressing and pressed ware handling instrumentalities. For this purpose, it is preferred to use pressing means which can readily be attached to and removed from permanent operating parts of the narrow neck machine so that the narrow neck forming instrumentalities, which as usual are removable, may be replaced when desired. It has been found in practice that in this way the machine can be changed from the production of narrow neck ware to the production of purely pressed ware (or vice versa) in normal job-change time, that is, within the period usually necessary to change molds and other parts when the machine is used only in the production of different kinds of narrow neck ware.

Other objects of the invention will be brought in, or will become apparent from, the description of an embodiment of the invention illustrated in the accompanying drawings, wherein:

Figure 1 is a view in vertical sectional elevation of a portion of a narrow neck machine embodying the invention, parts being omitted for clarity in illustration;

Fig. 2 is a similar view on enlarged scale, showing in detail the means for pressing the ware;

Fig. 3 is a view similar to Fig. 2, but showing in detail means for receiving, cooling and discharging the pressed ware from the machine; and

Fig. 4 is a view illustrating the operation of supporting and cooling an article of ware in preparation for its discharge from the machine.

For purposes of illustration and not in limitation of the invention, the illustrated embodiment (Fig. 1) consists of the adaptation of the invention to one section of the Hartford Individual Section Machine, disclosed in the patent to H. W. Ingle, No. 1,911,119, dated May 23, 1933, it being understood that the same adaptation 10 may be made to any number of sections of such machine.

As shown in Fig. 5 of the Ingle patent, each section of such machine comprises a blank mold and neck pin located at the blank forming station and with which cooperate a delivery funnel, a settle blow head and a neck mold. These and the other narrow neck forming devices are removably attached to their respective operating members for the purpose, but only for the purpose, of substituting other similar devices in changing from the production of one size or style of narrow neck ware to another.

Similarly, as shown in Fig. 1 herein, the base of the machine 6 supports vertical shaft 7 for the 25 holders, one of which appears at 8 which in Ingle carry the blank mold sections. At 9 is shown what in Ingle constitutes the neck pin operating mechanism, at 11 (Fig. 2) Ingle's funnel carrying arm, (in which funnel 12 of the present invention 15 is removably secured by ring 13), at 14 an arm similar to Ingle's settle blow head arm and at 15 Ingle's inverting neck mold carrying and transfer arm.

Each section of the machine of the patent also 35 includes a blow mold at the finish blowing station and hence Fig. 1 herein shows the vertical shaft 16 for the sections of such mold of the patent (not shown), and the member 17 for tilting the blow mold bottom plate (not shown) of 40 the patent. Also shown at this station is a finish blow head 18 and Fig. 1 shows at 19 the finish blow head operating arm both substantially as shown in the patent to Ingle.

The operation of the actuating or carrying 45 members of the narrow neck machine will be explained hereinafter, it being desired first to describe the utilization of such members in the operation of pressing and pressed ware handling devices.

Referring to Figs. 2 and 3, it will be seen that the neck mold carrying arm has removably fitted therein a sectional holder, as indicated at 21, which carries the sections of pressing mold 22, and a solid mold bottom or closure 23, to form 55

- 5 a mold cavity of the shape desired, in this instance for forming a threaded fuse case. The mold bottom 23 has a lug 24 thereon which is received in an opening 25 of the neck pin mechanism 9, whereby the latter serves to center the mold bottom and the mold 22 for registration with pressing ring 26. As will be apparent from Fig. 2, mechanism 9 serves as a support or rest for the pressing mold during the operation of pressing.
- 10 Ring 26 is secured in and forms part of funnel 12 by screw means, as shown, and these parts receive therethrough pressing plunger 27, for the operation of which the plunger carrying arm 14 is employed.
- 15 The plunger assembly includes casing 28 removably secured in known manner in the arm 14, as by means of lugs and flanges or a bayonet joint, as partially shown, this casing containing spring pressed plunger sleeve 29 which fits into 20 funnel 12 and in which plunger carrier 31 is slidably mounted under pressure of spring 32 in cage 33 on the casing. The downward movement of the plunger assembly is stopped by spring 34 engaging shoulder 35, the degree of pressure 25 applied to the plunger depending upon the strength of spring 32, as will be understood.
- To insure that the mold sections 22 will remain closed during the pressing operation, the blank mold carrying arms 8 (Fig. 2) are employed as 30 a mold lock to the holders 21 for the mold sections.
- The funnel carrying and plunger carrying arms 11 and 14 are oscillated and lowered by the shafts upon which they are mounted by means shown 35 in detail in the Ingle patent. Said patent likewise discloses means for vertically adjusting the neck pin operating mechanism 9 which is held in fixed position for centering the mold bottom 23, and the means for operating holders 8, as well 40 as the mechanism for inverting arm 15. Such mechanism is partially shown in Fig. 1 and includes oscillating shaft 37 carrying gear 38 engaged by rack 39 which is reciprocated by a piston (not shown) in cylinder 41.
- The mechanisms for oscillating and lowering finish blow head 18 and the bottom plate carrying member 17 also are shown in detail in the Ingle patent. The functions of these members in making pressed ware are as follows.
- The inverting of arm 15 inverts the press mold into the position shown in Fig. 3 in registry with discharge member 43 which replaces the blow mold at the finish blowing station, whereupon the finish blow head is lowered to engage opening 42 therein with lug 24 on the mold bottom 23 for centering the latter and stripping the pressed article from mold 22. At this position, the mold is opened in the same way as in releasing a blank for a narrow neck article, preferably by the means provided in the Ingle patent for opening the neck ring of the narrow neck machine. This serves to deliver the pressed article to the ware cooling and discharge device 43.
- This device 43 is removably secured to the bottom plate carrying member 17 by a bayonet joint indicated at 44, and its upper end is shaped to conform to the interior of the pressed article, as indicated at 45. In order to support and cool the pressed article, and out of contact with member 70 43, an air jet is delivered through orifice 46 in member 43 into the cavity of the article. This serves to hold the article out of chilling contact with the discharge member 43, as illustrated in Fig. 4. While so held, cooling air may be applied to the article from opposed nozzles 47-47.

Thus the article is cooled both internally and externally. When cooled to the desired degree, discharge member 43 is moved vertically downwardly to clear the mold 22 and then tilted by the operation of the mechanism normally used for lowering and tilting a bottom plate. The details of such mechanism may be best understood by reference to the Ingle patent. It is sufficient to explain here that member 17 is pivoted at 48 and is held in horizontal position by 10 spring 49 until moved vertically downwardly the length of slot 51, whereupon member 17 is tilted into the dotted line position of Fig. 3. These operations are caused by a piston (not shown), the rod 52 of which is connected to member 17 15 by links, one of which appears at 53. Such movement delivers the article to a slide 54 having a slot 55 therein, through which works discharge device 43. The article comes to rest on a dead plate 56 and is then pushed onto conveyor 57 by 20 a pusher indicated at 58.

Various types of pressed ware may be produced by the machine embodying this invention and changes made in the construction and operation of the several parts without departing from the 25 scope of the appended claims. The design of discharge device 43 may be changed to suit different types of ware.

From the above description and the drawings, it will be seen that my invention provides novel 30 means whereby a narrow neck machine may be employed in producing either narrow neck ware or purely pressed glassware, the instrumentalities for producing the one type of ware being quickly and easily replaced by the devices for making 35 the other type of ware. Also, exchangeable devices may be used for making different kinds of pressed ware.

It has not been considered necessary to illustrate herein timing mechanism for timing the 40 automatic operation of the various parts of the machine with each other and with the feeder (not shown) for delivering successive charges of glass to funnel 12 because timing mechanism for this purpose is disclosed in the patent to Ingle 45 referred to above and by simple adjustments is employed in the production of either pressed ware or narrow neck ware, as desired.

Certain subject matter disclosed in this application also is disclosed and is claimed in my co-pending application, Serial No. 310,100, filed December 20, 1939.

I claim:

1. A glassware forming machine comprising 55 mold carrying, funnel carrying and plunger carrying members, a press mold, a funnel and a plunger removably attached to said members respectively, a support, a ware discharge device removably connected to said support, and means for supporting and operating said members and support to bring said press mold, funnel and plunger into cooperative relation at a first position for the delivery of a charge of glass to, and the pressing of said charge into an article in, said press mold at said position, to invert said press mold about a horizontal axis to a second position, to hold said ware discharge device at said second position to receive said article from said press mold, and to operate said device to discharge said article from the machine. 65

2. A glassware forming machine comprising an arm, a press mold removably attached to said arm, means for pivotally supporting said arm, means for turning said arm to move said mold from a first position in which a charge of glass 75

is delivered to, and pressed into an article in, said mold to a second position in which said mold is inverted for the release of the article therefrom, first and second operating members, a 5 funnel and a pressing ring removably attached to said first member, a pressing plunger removably attached to said second member, means for supporting and operating said members to move said funnel and plunger into cooperative relation with said press mold to deliver a charge of 10 glass to, and press it into an article of glassware in, said press mold at the first position, a support, a ware discharge device removably attached to said support, and means for operating 15 said support to hold said device at said second position to receive said article from said press mold and to move said device to discharge said article from said machine.

3. A glassware forming machine comprising 20 mold carrying, funnel carrying and plunger carrying members, a press mold, a funnel and a plunger removably attached to said members respectively, means for supporting said mold carrying members for movement about a horizontal axis from a first position to a second position, means for oscillating and lowering said funnel and plunger carrying members to move 25 said funnel and plunger into cooperative relation

with the press mold for the delivery of a charge of glass to, and the pressing of said charge into an article in, said press mold at the first position, means for swinging said mold carrying member about said horizontal axis to bring said mold 5 with the article therein to said second position, a support, means for mounting said support for tilting and descending movements, a ware discharge device removably attached to said support, and means for operating said support to 10 hold said device in position to receive said article from said mold and to tilt and lower said device to discharge said article from the machine.

4. A glassware forming machine as recited in 15 claim 1 comprising means for holding said press mold in predetermined vertical axial position at said first position.

5. A glassware forming machine as recited in 20 claim 1 comprising means for holding said press mold in predetermined vertical axial position at said first and second positions.

6. A glassware forming machine as recited in 25 claim 1, said press mold being formed in sections, and means for holding said mold closed while an article is being pressed therein at said first position.

WALTER K. BERTHOLD.
